UNITED STATES PATENT OFFICE.

ROBERT A. MANEGOLD, OF MILWAUKEE, WISCONSIN, ASSIGNOR TO DINGS MAGNETIC SEPARATOR CO., OF MILWAUKEE, WISCONSIN, A CORPORATION OF WISCONSIN.

MAGNETIC SEPARATOR.

Application filed August 18, 1922. Serial No. 582,626.

To all whom it may concern:

Be it known that I, ROBERT A. MANEGOLD, a citizen of the United States, and resident of Milwaukee, in the county of Milwaukee and State of Wisconsin, have invented certain new and useful Improvements in Magnetic Separators; and I do hereby declare that the following is a full, clear, and exact description thereof.

10 This invention relates to magnetic separators, or pulleys, and is particularly directed to a heavy duty pulley.

15 In magnetic separator practice considerable difficulty has been encountered in producing a pulley capable of continuously operating at its maximum efficiency or capacity without dangerous overheating. Various attempts have been made to increase the heat dissipation by increasing the 20 metallic exposed surface of the pulley. These attempts have failed to furnish an adequate solution of this problem, primarily for the twofold reason that a more bulky pulley necessarily results, and the hottest 25 part of the exciting winding,—its central portion,—is still uncared for.

20 This invention is designed to overcome those difficulties and a primary object, therefore, is to provide a magnetic pulley which 30 of the flux along the peripheral portion of the pulley.

35 This invention is designed to overcome those difficulties and a primary object, therefore, is to provide a magnetic pulley which 40 fully solves these problems.

Further objects are to provide a magnetic pulley in which provision is made for adequately cooling the hottest portion of the exciting windings, to provide a maximum 45 radiating surface, to allow the cooling medium to pass through the exciting windings themselves, and to provide for the direct contact of the cooling fluid with the exciting windings.

50 Further objects are to provide a magnetic pulley in which maximum current density may be safely employed, in which maximum flux density is attained, and in which a better and substantially uniform flux distribution along the peripheral portion of the pulley is secured.

Embodiments of the invention are shown in the accompanying drawings, in which:

Figure 1 is a longitudinal sectional eleva-

tion of a magnetic pulley, showing one form 55 of the invention.

Figure 2 is a transverse sectional view with parts broken away, such section being taken vertically thru the pulley shown in Figure 1.

Figure 3 is a fragmentary sectional view taken on the line 3—3 of Figure 2.

Figure 4 is a horizontal view of a drum type of magnetic pulley, such section corresponding to that taken on the line 4—4 65 of Figure 5.

Figure 5 is a vertical sectional view thru the structure shown in Figure 4, parts being broken away to more clearly illustrate the construction.

The invention shown in Figures 1, 2 and 3 will first be described. The magnetic pulley shown in these figures is adapted to cooperate with a conveyor belt 1, which is supplied with material to be separated from 75 any suitable hopper or other source of supply in a well known manner. The pulley shown may be the driving pulley, if desired, or the pulley supporting the other end of the belt may be the driving pulley.

The magnetic pulley is carried upon a shaft 1', provided with suitable slip rings 2 suitably connected to the exciting windings. In the form shown in Figure 1, the central portion of the magnetic section of 85

the pulley comprises a hollow cylinder 3 of magnetic material supported at each end by a plurality of spokes merging into a hub 4. One or both of the hubs may be suitably keyed to the shaft. A plurality of central 90

flanges 5 of magnetic material are accurately fitted to the hub and are secured in place by means of a plurality of elongated screws 6, the threaded portions of which are screwed into the central section 3. Between each of the flanges 5, exciting coils 95

are wound, such coils, of course, being wound concentrically with the pulley. These exciting windings may comprise a plurality of independent windings or sections of the 100 main winding, and may be formed so as to provide a pair of relatively small coils 7 and 8, positioned next to the cylinder portion, and a relatively thicker or wider coil

9, surrounding the coils 7 and 8.

It is to be noted that these coils, or sections of each successive windings between the flanges, are spaced apart so as to provide

a plurality of radial passages 10, and a plurality of longitudinal or horizontal passages 11. These passages or ducts communicate with ports or ducts 12 and 13, formed, respectively, in the central portion 3 and in the flange portions 5. In this manner a plurality of inter-communicating ventilating ducts are provided thru which a cooling fluid may be passed. As shown in Figure 1, the pulley, when rotating, causes air to be drawn into the central hollow portion 3 thru its ends, and to be passed radially thru the passages 10 and into the horizontal passages 11, as shown by the arrows. This causes a constant current of cooling air to circulate thru the interior of the windings themselves, and passes this cooling stream of air thru the part or central portion of the coil which, as is well known, is the "hot zone," or hottest portion of the coil. It will be seen that the usual radiation from the metallic surfaces of the pulley takes place, and in addition to this, a vast amount of heat is carried away by the circulating cooling medium directly from the windings themselves.

In order to maintain the sections 7, 8 and 9 of each of the exciting windings in their proper position, and also in order to facilitate the manufacture of the pulley, the following method is employed:—A plurality of spaces 14 are positioned radially, as shown in full lines in Figure 1 and in dotted lines in Figure 2, and the coils 7 and 8 are wound in position. These members or separators 14 are widely spaced so as to provide a plurality of radially extending ducts therebetween. When the windings 7 and 8 have been completed, a relatively short horizontal separator or spacer 15 is laid on top of such windings, and the outer winding 9 is then formed directly over these members. These separators 15 may be circular, rectangular or arcuate in cross sectional contour, and are adapted to be widely spaced so as to form a plurality of horizontal or longitudinal ducts communicating with the radial ducts. The flanges may be provided with a plurality of independent and relatively small ducts or with a plurality of arcuate ducts 13, as shown. At one end of the ducts 13 upon the end flanges, cup shaped fan members 16 are provided and may be integrally formed with the end flanges, as shown. If it is desired to have the circulation in the direction shown by the arrows in Figure 1, it may be found expedient to put these cup shaped members at the leading edges of the arcuate slots 13, so as to cause a suction to be exerted, this suction, of course, cooperating with the centrifugal fan action of the radial duct 10. It is, of course, within the province of this invention to provide any type of fan means desired, and to have the

circulation in any desired direction thru the radial and longitudinal ducts.

The windings are protected by a series of sheets or shells 17, which are formed of magnetic material and which are of relatively thin cross section. These protecting bands are seated within slotted shouldered portions adjacent the outer periphery of the flanges, as may be seen in Figure 1. The pulley may be provided with terminal or end flanges 18 to provide an extra support for the edges of the conveyor or belt 1. These flanges may or may not be of magnetic material.

It is, of course, understood that the ventilating feature may be applied to pulleys provided with non-magnetic bands in place of the magnetic bands 17. When, however, the magnetic bands or protecting shells 17 are employed, the flux distribution is greatly improved, as they serve to more uniformly distribute the flux along the periphery of the pulley. It is found that the leakage directly across from flange to flange and thru these bands is not of serious consequence, as the bands are substantially saturated, and that the flux passes outwardly into the surrounding medium in a very uniform and well distributed manner. Any suitable means may be employed for securing the protecting members 17 against sliding motion.

The invention disclosed in Figures 4 and 5 will now be described. The pulley shown in these figures is of the drum type, in which the hollow body portion or central portion 19 is adjustably held in a stationary position by any suitable external means, (not shown). About this central portion, a drum or protecting shell 20 of magnetic material is adapted to be rotated, such shell being spaced a slight distance from the outer periphery of the internal magnet members. This drum is carried upon shouldered portions 21 of end flanges 22, which are provided with hub sections 23, suitably bushed and adapted to rotate upon the member 19. One of the end flanges is adapted to have a driving member such as gear 24, (see Figure 4) secured thereto. These terminal flanges are provided with a plurality of apertures 25, placing the interior of the drum in free communication with the exterior so as to permit the free circulation of any desired cooling medium.

The magnets are formed in a manner similar to that shown in Figure 1, by providing a plurality of spaced flanges 26 secured in any suitable manner, as by means of screws 27 upon the central magnetic member 19. These flanges adjacent the forward or downwardly traveling side of the drum 20, are extended, as shown in Figure 5; upon the opposite side, that is to say, the side corresponding to the upwardly travel-

ing portion of the drum, the flanges are cut away, as indicated at 28. This provides a strong magnetic field along the downwardly traveling side of the drum and slightly past the bottom or lower portion so as to retain the magnetic material against the outer periphery of the drum until such drum has carried it past the bottom central portion. At this point, the magnetic material falls from the surface of the drum as the magnetic field dies out, due to the cut away formation of the flanges.

In forming the exciting windings in this type of pulley, a plurality of relatively short radial separators or spacing members 29 are positioned, and the first pairs of sections 30 and 31 of the windings are formed, as may be seen from Figure 4. After these windings have been completed, a plurality of horizontal separators or spacers 32 are laid on top of these coils and the next set of pairs of sections 33 and 34 are formed, suitable radial spaces or separators 35 being provided. It is to be noted, from Figure 4, that spacers 36 are also positioned between successive exciting windings to supplement the cutaway portions of the flanges and to securely position and space the adjacent portions of the exciting windings. In this manner, a plurality of radial ducts 37 and horizontal ducts 38 are provided, and are placed in intercommunicating relation with each other, the radial ducts opening into ports or ducts 39 formed in the central member 19, and the longitudinal ducts opening into ports or ducts 40 formed in the flanges 26.

It will be seen that in this type of pulley, a series of radial and longitudinal ventilating or cooling ducts are provided in a manner similar to that described in connection with Figure 1. However, in this type of pulley, the radial ducts are extended and pass outwardly beyond the periphery of the windings and open into the space between the drum 20 and such windings.

Although fan means have not been shown in connection with this pulley, it is obvious that any suitable type may be employed, if desired. It is also to be understood that the ventilating feature of this type of pulley may be applied to pulleys in which the drum is of nonmagnetic material.

The drum 20, as described, is preferably of magnetic material so as to aid in the proper distribution of flux along the entire periphery of the pulley in a manner similar to that described in connection with Figure 1, and it is intended that the terms employed in the claims to designate the protecting sheets or members 17 and 20, are intended to cover both types of protecting members, unless otherwise specifically limited by the terminology of the claims.

The separators or spacers may be formed of any desired material, preferably of a

non-magnetic and electrically non-conducting nature. They may, for instance, be formed of wood, fiber or any other insulating material, or may be formed of suitably coated or insulated metallic material.

Although the body portion has been illustrated as composed of a central member and separate flanges secured thereto, it is of course obvious, that the flanges and body portion may be formed integrally, if desired, without departing from the spirit of the invention.

It will be seen that a magnetic pulley has been provided in which any desired type of cooling medium may be employed, and may be passed directly thru the windings themselves. In this manner the hottest portion of the exciting windings or coils is cooled directly and without depending upon the relatively inefficient conduction thru the body of the coil and into the metallic structure of the pulley.

It will be seen, therefore, that a very high current density may be employed for the windings, and a correspondingly high flux density may be secured by these pulleys, thereby providing pulleys capable of continuous heavy duty work without dangerous overheating.

It will also be seen that by the provision of the protecting sheets 17 and 20 of these pulleys, that a highly efficient flux distribution is secured throughout the entire periphery of the pulley, and that the consequent poles of the magnet cooperate with these protecting sheets so as to secure the maximum total flux and a substantially uniform flux distribution.

Although certain forms of the invention have been described in considerable detail, it is to be understood that the invention may be embodied in widely different types of separators and that such invention is to be limited only as set forth in the appended claims.

I claim:

1. A magnetic pulley comprising end pieces having ventilating apertures therein, a central hollow member secured to said end pieces, windings upon said central member and between said end pieces, said windings being composed of a plurality of axially spaced sections and radially spaced sections, and spacing bars located between said sections, whereby ventilating ducts are provided in said windings between such spacing bars, said hollow center member having apertures aligning with certain of said ventilating ducts.

2. A rotary magnetic pulley comprising end pieces having arcuate ducts therethrough, vanes carried by said end pieces adjacent succeeding ends of said ducts and adapted to produce a circulation of air through said ducts, a hollow central member having aper-

tures therethrough, a winding positioned upon said central member and between said end pieces, said winding being formed of a plurality of annular sections separated by horizontal spacing rods and having a plurality of axially spaced sections separated by radial spacing members, and said hori-

zontal ducts communicating with said arcuate slots in the end members.

In testimony that I claim the foregoing ¹⁰ I have hereunto set my hand at Milwaukee, in the county of Milwaukee and State of Wisconsin.

ROBERT A. MANEGOLD.
